H. SIEBEN.

FLUID CONTROLLING APPARATUS,
APPLICATION FILED DEC. 29, 1911.

Patented Feb. 1, 1916.

UNITED STATES PATENT OFFICE.

HENRY SIEBEN, OF KANSAS CITY, MISSOURI.

FLUID-CONTROLLING APPARATUS.

1,169,877

Specification of Letters Patent.

Patented Feb. 1, 1916.

Application filed December 29, 1911. Serial No. 868,440.

To all whom it may concern:

Be it known that I, HENRY SIEBEN, a citizen of the United States, residing at Kansas City, in the county of Jackson and State of Missouri, have invented certain new and useful Improvements in Fluid-Controlling Apparatus, of which the following is a specification.

My invention relates to fluid controlling apparatus, and my object is to produce new and useful apparatus of this character whereby gas or other fluid may be cut off from a building either manually or automatically.

The apparatus includes a valve to control the flow of fluid through the service-pipe leading into the building, and means to control said valve, and in order that the invention may be fully understood, reference will now be made to the accompanying drawing, in which:

Figure 1 is a broken vertical section partly in elevation, of my apparatus. Fig. 2 is an irregular vertical section of a portion of the apparatus on line II—II of Fig. 1. Fig. 3 is a cross section of a valve, on line III—III of Fig. 2, employed in carrying out the invention. Fig. 4 is a rear elevation of the upper end of a lever and its connecting parts, employed in carrying out the invention. Fig. 5 is a broken vertical section on line V—V of Fig. 1. Fig. 6 is a broken elevation of a modified form of the invention.

In carrying out the invention I employ a valve 1, which is preferably self-closing. Said valve communicates with the service-pipe 2 leading from the street main into the building (not shown), and is preferably, placed in a pit 3, located outside the foundation of the building and provided with a lid 4 through the removal of which access may be had to the interior of said pit. The valve is further inclosed in a casing 5, so that it cannot be tampered with by unauthorized persons who might remove the lid 4 from the pit.

The valve is provided with a weighted-lever 6, whereby it is closed, and the free end of said lever is provided with a slotted stop 7 adapted to contact with an arm 8 to prevent straining the valve after the same is closed. Arm 8 is secured to the underside of the valve by a screw 9, the upper pointed terminal of which projects into the valve and forces the valve-plug 10 firmly against its seat 11 when the valve closes. Valve-

plug 10 is removably-secured to a reciprocable rack 12, actuated by a segmental gear 13, fixed upon a rock-shaft 14 journaled in the valve casing and projecting laterally therefrom through a stuffing-box 15, to receive the lower end of lever 6, which is secured thereto.

A reinforcement 16 opposite the segmental gear 13 prevents rack 12 from bending laterally under stress exerted thereon by said segmental gear 13, and a guide 17 integral with said rack and operably-engaging a guide 18 in the valve casing, prevents said rack from turning axially out of engagement with the segmental gear. Stop 7 is pivotally-secured by a pin 19, to lever 6 and has shoulders 20 and 21 to engage a pin 22 to retain said stop in a substantially horizontal position throughout the downward movement of the weighted end of the lever. Lever 6 is normally held in raised position,

to hold the valve open, by a fusible link 23 and a pin 24, which latter extends through an opening in one end of the link and a pair of ears 25 projecting laterally from the upper portion of a tubular guide 26, at the upper end of the valve casing to guide rack 12 in its up and down movement. Pin 24 is connected to a crank-arm 27, through the intermediary of a cable 28, said crank-arm being secured to the lower end of lever 6, as shown in Fig. 1. Pin 24 has an eye in its upper end to receive one end of a lever 29 fulcrumed upon a pin 30 at the upper end of an arm 31, secured to the tubular guide 26. The opposite end 31 of lever 29 is bifurcated and said lever is jointed at 32, so that its bifurcated end 31 may have independent upward movement, for a purpose which will hereinafter appear.

33 designates a rod whereby the valve is manually controlled, said rod being provided at its lower end with a spool-shaped member 34, having a flange 35 overlapping the bifurcated end of lever 29. Spool 34 is secured to the lower portion 36 of rod 33, said lower portion 36 being tubular, so that it may move downward upon a vertically-extending guide-rod 37, secured at its lower end to arm 8. Rod 33 extends through a conduit 38 leading from the upper portion of the pit to the lower end of a box 39, into which the upper portion of the rod extends, so that it cannot be tampered with. When it is inconvenient to locate the box 39 immediately over the pit 31, it is necessary to

make the conduit 38 more or less tortuous, as shown in Fig. 1, and in order that the rod may follow such conduit, its intermediate portion is made flexible, as indicated at 40.

- 5 The upper end of the rod is bent at right angles thereto to form a handle 41, adapted to rest upon the upper end of a safety-member 42 to hold the rod in raised position. Safety-member 42 is secured to the bottom 10 of the box, which is provided with a lid 43 having a notch 44 to fit over a staple 45, adapted to receive a lock to secure the door in closed position. In some instances the door may have a glass front, so that it may 15 be broken in case of emergency, if desired, to gain access to the handle 41.

In practice, box 39 is preferably located outside of the building, or other accessible point, so that it can be easily found when 20 it is desired to close the valve and cut off gas to a burning building.

- The operation of the apparatus briefly stated, is as follows: To cut off the flow of gas or other fluid into a building on account of fire, or for any other reason, door 43 of the box is either unlocked or broken open and handle 41 is grasped, raised up out of engagement with the upper end of the safety-member 42 and turned forward to 25 clear said safety-member. The rod 33 is then pushed downward to actuate lever 29 and cause the same to withdraw the pin 24 from the fusible link 23 and the guides 25. The instant the fusible link 23 is released 30 from the pin 24, the weighted-lever 6 automatically closes the valve and thus cuts off the flow of fluid into the building through the service-pipe 2. Should the valve, for any reason, fail to close when the fusible 35 link 23 is released from pin 24, continued downward movement of the rod 33 tips the opposite end of lever 29 upward enough to close the valve through the intermediary of pin 24, cable 28, and the crank-arm 27. 40 Should the last-mentioned operation fail to close the valve by reason of the lever 29, cable 28, or crank-arm 27, getting out of order, the valve will be positively closed by continued downward movement of rod 33, 45 which upon passing the bifurcated end 31 of lever 29 comes into contact with the slotted stop 7, so that sufficient pressure can be exerted thereon to close the valve without fail. After the valve has been closed, it can 50 not be strained or otherwise injured by further downward pressure of the rod 33, as further downward movement of said rod is checked by its handle 41 striking the bottom of box 39, and spool 34 striking the 55 slotted stop 7, which stop is held from further downward movement by the arm 8, upon which its rests. To open or reset the valve, handle 41 is grasped and drawn upward and turned inward into engagement 60 with the upper end of the safety-member 65

42, carrying the rod 33 upward therewith and supporting the same in its raised position, as shown in Fig. 1 of the drawing. As the push-rod 33 moves upward, flange 35 of spool 34 passes above the bifurcated end 31 of lever 29 by moving said bifurcated end upward on the pivot 32, and immediately after flange 35 passes above said bifurcated end 31, the same is automatically restored to normal position (see Fig. 1), by its counterweight 31^a and spring 31^b. Weighted-lever 6 is then swung upward to open the valve, and held in raised position by the pin 24, the reduced lower end of which is inserted through the fusible link 23 and the guides 25. Should a fire originate close to the valve and fuse the link 23, the valve is automatically closed by its weighted-lever 6.

Cable 28 and crank-arm 27 are used chiefly as precautionary measures to insure closing of the valve manually, and may be dispensed with, as may also the fusible link 23, when the pit containing the valve is located outside of the building, therefore I wish it understood that I do not restrict myself to the exact details of construction disclosed and described, as various modifications will suggest themselves to one skilled in the art.

Having thus described my invention what I claim and desire to secure by Letters patent, is:

1. In an apparatus of the character described, a service pipe for conducting fluid into a building, a self-closing valve to control the flow of fluid through said service pipe, means to assist in normally holding said valve open, fusible means coacting with the first-mentioned means to normally hold the valve open, and a push-rod to actuate said first-mentioned means to allow the valve to close.

2. In an apparatus of the character described, a service pipe to conduct fluid into a building, a self-closing valve to control the flow of fluid through said service pipe, means to normally hold said valve open, a rod to actuate said means to allow the valve to close, said rod having a handle, a box inclosing said handle, and a safety-member which holds the handle in position to prevent closing of the box until said handle is restored to normal position.

3. In an apparatus of the character described, a service-pipe for conducting fluid into a building, a self-closing valve to control the flow of fluid through said service pipe, a pin coacting with the casing of the valve to normally hold the valve in open position, and a rod to retract said pin and simultaneously force said valve to its seat.

4. In an apparatus of the character described, a service-pipe for conducting fluid into a building, a self-closing valve to control the flow of fluid through said service

pipe, said valve including a weighted-lever, a fusible element connected with said lever to assist in normally holding the valve open, a pin coating with said fusible element in normally holding the valve open, and manually-operable means to actuate said pin to release the lever and allow the valve to close.

5 6. In an apparatus of the character described, a service-pipe for conducting fluid into a building, a self-closing valve to control the flow of fluid through said service pipe, said valve including a weighted-lever, a fusible element connected with said lever to assist in normally holding the valve open, 10 a pin coating with said fusible element in normally holding the valve open, a lever to actuate said pin to release the lever and allow the valve to close, and manually-operable means to actuate said lever.

15 7. In an apparatus of the character described, a service-pipe for conducting fluid into a building, a self-closing valve to control the flow of fluid through said service pipe, said valve including a weighted-lever, 20 a fusible element connected with said lever to assist in normally holding the valve open, a pin coating with said fusible element in normally holding the valve open, and a push-rod to actuate said pin to release the 25 lever and allow the valve to close.

25 8. In an apparatus of the character described, a service pipe for conducting fluid into a building, a self-closing valve to control the flow of fluid through said service 30 pipe, said valve including a weighted lever, a fusible element connected to said lever to assist in normally holding the valve open, a pin coating with said fusible element in normally holding the valve open, a lever to 35 actuate said pin to release the lever and allow the valve to close, and a push-rod to 40 actuate said lever.

45 9. In an apparatus of the character described, a service pipe for conducting fluid into a building, a self-closing valve to control the flow of fluid through said service pipe, said valve including a rock-shaft and a lever mounted thereon, a pin coating with the lever to normally hold the valve open, 50 manually-operable means to actuate said pin to release the lever and allow the valve to close, and means connecting said pin and the valve whereby the latter is positively closed when said pin is actuated.

55 10. In an apparatus of the character described, a service pipe for conducting fluid into a building, a self-closing valve to control the flow of fluid through said service pipe, said valve including a rock-shaft and a lever mounted thereon, a pin coating with the lever to normally hold the valve open, 55 manually-operable means to actuate said pin to release the lever and allow the valve to close, a crank-arm fixed to the lever and a 60 collar connecting said crank-arm and the pin

whereby the valve is positively closed when said pin is actuated.

10 11. In an apparatus of the character described, a service pipe to conduct fluid into a building, a self-closing valve to control the flow of fluid through said service pipe, means to normally hold said valve open, a lever engaging said means, a push-rod to actuate said lever whereby said means is actuated to allow the valve to close, said 70 push-rod being tubular at its lower portion, and a guide for said tubular portion of the push-rod.

15 12. In an apparatus of the character described, a service pipe for conducting fluid into a building, a self-closing valve to control the flow of fluid through said service pipe, said valve including a lever, a slotted member on said lever, an arm projecting from the lower portion of the valve against 80 which said slotted member is adapted to contact when the valve is closed, a guide extending upward from said arm through said slotted member, means to normally hold the lever in position so as to hold the valve open, 85 and a push-rod to actuate said means to release the lever and allow the valve to close, said push-rod operably-engaging the guide and adapted to contact with the slotted member on the valve-lever. 95

100 13. In an apparatus of the character described, a service pipe to conduct fluid into a building, a self-closing valve to control the flow of fluid through said service pipe, a pin to normally hold said valve open, a lever to actuate said pin to allow the valve to close, said lever having a jointed portion normally held in alignment therewith, and a push-rod to actuate said lever, said push-rod having a spool at its lower portion to engage said lever, the jointed portion of which latter permits the push-rod and its spool to be restored to normal position after the spool has been pushed downward beyond the lever to close the valve. 110

105 14. In an apparatus of the character described, a service pipe to conduct fluid into a building, a valve to control the flow of fluid through said pipe, means to hold said valve open and a rod to release said means 115 and force the valve to its seat.

110 15. A cut off valve comprising a valve casing, a valve normally tending to seat therein; a detent for holding said valve open, and means adapted to retract said detent and simultaneously force said valve positively to its seat. 120

115 16. A cut off valve comprising a valve casing, a valve normally tending to seat therein; a detent supported independently of the valve for holding said valve open, and means adapted to retract said detent and simultaneously force said valve positively to its seat. 125

120 17. In a safety valve mechanism for gas 130

or water mains, a valve provided with means for automatically forcing it from an open to a closed position, a movable member provided with means for releasably engaging and normally holding the valve in the open position, and operating means for moving said member to release the valve, the operating means being provided with means for engaging and moving the valve to closed position if the valve fails to automatically move to the closed position after its release from said member.

17. In a safety valve mechanism for gas or water mains, a valve provided with means for automatically forcing it from an open to a closed position, a lever provided with means for releasably engaging and normally holding the valve in the open position, and operating means for swinging the lever to release the valve and having means when operated for closing the valve when the valve fails to close automatically.

18. In a safety valve mechanism for gas

and water mains, a reciprocating valve having a lever provided with means for moving the valve automatically from an open to a closed position, a movable member provided with means for releasably engaging said lever to hold the valve in the open position, and means for moving said member to release the lever and for moving the valve to the closed position if the valve fails to close after its release from said member.

19. A cut off valve comprising a valve casting, a reciprocating valve tending normally to close therein, a detent supported independently of the valve for holding the valve open, and means adapted to release the detent from the valve and to force the valve positively to a closed position.

In testimony whereof I affix my signature, in the presence of two witnesses.

HENRY SIEBEN.
